UNITED STATES PATENT OFFICE.

ALFRED WEILAND, OF EAST ORANGE, NEW JERSEY.

CARBURETER FOR INTERNAL-COMBUSTION ENGINES.

1,274,964.

Specification of Letters Patent.

Patented Aug. 6, 1918.

Application filed February 17, 1917. Serial No. 149,165.

To all whom it may concern:

Be it known that I, ALFRED WEILAND, a citizen of the United States, residing at East Orange, county of Essex, and State of New Jersey, have invented a certain new and useful Improvement in Carbureters for Internal-Combustion Engines, of which the following is a specification.

The present invention relates generally to 10 the control, regulation and feeding of liquid fuel to explosive engines and relates more specifically to the supply of liquid fuel to the carbureter or carbureting medium and the discharge of such fuel to the motor

15 intake.

It is an object of the invention to provide automatic means for maintaining a supply of liquid fuel available at all times, and under the control of pressure conditions, to furnish the requisite fuel to the carbureting chamber for the use of the motor.

It is a further object to provide fuel feeding means which automatically vary 25 according to speed and load conditions so that such conditions, as flooding the carbureter when a minimum supply is required and having it relatively empty when a maximum supply is needed, are entirely 30 overcome.

A further object of the invention is to provide a complete unitary fuel feeding device, the parts of which have a common housing or casing forming compact fuel 35 receiving, storing, and carbureting chambers and wherein pressure conditions are utilized to automatically replenish the liquid fuel exhausted by use, such replenishing taking place without obstructing or 40 interfering with the regular and continuous feeding to and operation of the liquid fuel jet or nozzle.

For the purpose of illustrating my invention, I have shown in the accompanying 45 drawings one form thereof which is at present preferred by me, since the same has been found in practice to give satisfactory and reliable results, although it is to be understood that the various instrumentalities of 50 which my invention consists can be variously arranged and organized and that my invention is not limited to the precise arrangement and organization of the instrumentalities as herein shown and described.

55 Referring to the drawings:

Figure 1 represents a plan of a carbureter embodying my invention, the throttle lever being omitted.

Fig. 2 represents a section on line 2—2 of Fig. 1.

Fig. 3 represents a section on line 3—3 of Fig. 1.

Fig. 4 represents a section on line 4—4 of Fig. 1.

Fig. 5 represents a sectional elevation of 65 a modified form of the carbureter.

Fig. 6 represents a section on line 6—6 of Fig. 1.

Fig. 7 represents a section on line 7—7 of Fig. 1.

Fig. 8 represents a detail of one of the valve levers.

Fig. 9 represents a bottom plan of the valve levers.

1 designates the casing of the carbureter forming, in the present instance two float chambers 2 and 3 spaced by the intermediate body wall 4 in which the carbureting chamber 5 is formed. This chamber 5, as customary, communicates with the main air intake passage 6 at one end and with the motor intake 7 at the opposite end. Adjacent this latter end the throttle valve 8 is located and is under the control of the throttle lever 9 as will be understood. 85 The casing 1 is further formed with a main liquid fuel reservoir 10 located below the level of the two float chambers 2 and 3 and serving to supply the main jet or nozzle 11 with liquid fuel to be mixed with the air in chamber 5 and supplied to the motor. The liquid fuel for the reservoir 10 is supplied from either of the chambers 2 and 3, the action of replenishing being substantially alternately carried out, that is one 90 of the chambers is an active feeding medium for the reservoir 10 while the other chamber is replenishing its fuel supply from the main low level tank (not shown) located at a convenient point. 95

Considering first the construction of chamber 2 it will be noted that it is preferable, though not necessary, to provide means whereby its fuel volume is normally less than the fuel volume of the chamber 105 3 since this is the chamber which under working conditions is the active feeding agent for the reservoir 10.

The chamber 2 is provided with a fuel inlet 12 communicating with the main fuel conduit 13 which conveys the said fuel from the low level tank as will be understood.

As here shown, the wall 4 is provided with a boss 14 on the chamber side, through which the fuel inlet conduit passes, carrying a flap valve 15 in the nature of a flat plate held by the stud 16 with sufficient lost motion to permit it to open under fuel pressure but to be normally held closed.

17 designates the outlet for the fuel from the chamber 2 to the reservoir 10, the same having a seat at one side to receive the control valve 18. In the present instance the valve 18 is provided at one side with a relatively long stem 19 which is guided through a portion of the wall 4 and terminates in a ball jointed connection 20 to the float 21. The opposite side of the valve 18 has a split rod 22 and turn buckle 23 connection with a pivoted lever 24 for a purpose to be later described, and the rod ends join their respective parts by ball joints 25 which permit the required relative movement.

26 designates an unobstructed passage forming communication between the carbureting chamber 5 and the float chamber 2 above the normal liquid level in the said chamber 2 and consequently the chamber 2 is subject to some extent to the same vacuum conditions as exist in the chamber 5. Below the chamber 2, the casing 1 is suitably recessed to form an auxiliary overflow receiver 27 which prevents the liquid fuel from overflowing through the nozzle 11 into the carbureting chamber 5 when the motor is at rest or when the vacuum is broken in either of the chambers 2 and 3. An air vent 28 is provided to conduct air to the receiver 27 and maintain it under atmospheric conditions. A similar vent 42 for air is formed in the wall 4 and has its outlet 29 in relatively close proximity to the chamber outlet 17 and below the normal level of the liquid fuel. The float chamber 3 is substantially similar in details of construction as the chamber 2 and it is thought unnecessary therefore to more than point out the corresponding parts. Thus it has an outlet 30, a control valve 31 therefor, the long stem 32 connected by a ball joint with the float 33 also the split rod construction 34 and 35 joining the valve to a lever 36. It is also provided with a passage 37 for establishing vacuum conditions in the float chamber 3 and the fuel inlet 38 is controlled by a flap valve 39 similar to that for chamber 2. There is also the overflow receiver 40, its air vent 41 and the air passage 42 having an outlet below the fuel level adjacent the outlet 30.

60 In connection with the levers 24 and 36, it should be noted that arms 43 are provided respectively for engaging the opposite lever in order that the downward movement of either lever under the opening of one or the other of the valves 18 or 31 causes the mov-

ing arm to engage the adjacent lever and close the outlet valve of that lever. There is, however, sufficient lost motion in the valve connections to allow them to simultaneously open slightly if necessary.

70 Referring to Fig. 1, it will be seen that the main reservoir 10 extends beyond the wall of the casing on the throttle side and forms two auxiliary receptacles 45 and 46 the former being located adjacent the position of the throttle valve and having a jet 47 in which the liquid fuel is normally maintained at the level of the liquid level in the reservoir 10. It will be understood that both receptacles 45 and 46 are formed in an extension of the casing 1 and that each is chambered and in communication with the reservoir 10, so that each chamber, as a matter of fact, forms a part of the reservoir 10. 75 48 designates a suitable bushing secured to the casing 1 and extending within the chamber 45 and having a bore 49 therein to receive the nozzle 47 as appears in Fig. 3. The bushing 48 for the major part of its length is reduced in diameter in order to form a 80 channel by which the air entering through the port 50 may reach the open end of the bushing 48 and thus mix with the fuel drawn out of the jet 47. The bore 49 communicates with a conduit 51 which passes 85 through the casing wall and discharges the mixed air and fuel outside of the throttle, that is to say, between the throttle and the motor intake. The throttle valve is here designated by the reference numeral 8 and is connected to the rotatable sleeve 53, this latter being suitably pinned as shown at 54 or by like equivalent means to the spindle 55 which carries the throttle lever 9.

57 designates a bushing or sleeve fixed within the casing 1 and bored out to form the above mentioned chamber 46, the said bore having a reduced portion extending through the part 57 and communicating with the reservoir 10, so that the fuel flows freely into the chamber 46 to the normal level. In the present instance, the spindle 55 is provided with a passage 58 the inner end of which terminates below the liquid level while the outer end has free communication with the atmosphere and therefore forms a passage for air which is drawn in and bubbles through the liquid fuel and the resulting mixture is then drawn out into the carbureting passage 5 by way of the port 59 formed in a laterally disposed boss 60 connected to the throttle sleeve 53. By reference to Fig. 1, it will be seen that this port 59 discharges the mixture on the carburetor side of the throttle valve and that its discharge end is in close proximity to the wall of the chamber 5 when the throttle is in closed position, but as the throttle opens it moves nearer to the central portion of the chamber 5 so that the mixture drawn out of 100 105 110 115 120 125 130

the port 59 mingles with the body of the explosive mixture moving to the motor intake. This action is distinguished from an auxiliary fuel feeding outlet which is in the wall of the carbureting chamber, since in that case particles of the liquid fuel adhere to the walls and the value of the mixture considerably lessened.

Referring to Fig. 5 of the drawings, a modified type of carbureter is shown wherein the supplemental or reserve float chamber is somewhat varied in construction, though still within the broad principle of my invention, while the active float chamber 13 and its adjuncts remains unchanged and for that reason the same reference numerals are applied to the like parts of Fig. 5 as already applied to the parts of Fig. 2.

61 designates the supplemental float chamber which in the present instance, as compared to the float chamber 2 is relatively small but is provided with a discharge outlet 62 to allow the supply of liquid fuel to flow into the reservoir 10 according to requirements and this outlet as heretofore described is controlled by the valve 63 which is connected to the lever 64 and operated by the movement of the float 21. Since the lever 64 is a one-piece lever pivoted at substantially its middle point any movement of the valve stem 19 will be correspondingly transmitted to the valve 63 and that valve opened or closed, as will be understood. The fuel supply conduit 13 communicates with the upper portion of the float chamber by way of a passage 65 which is suitably drilled in the body of the casing and terminates in a valve seat 66 to receive the valve 67 of the float 68, and it will be understood that the float 68 is maintained in operative position with respect to the fuel supply conduit passage valve seat 66 by suitably guiding the float stem in the casing wall. A port 69 forms a communication between the carbureting chamber 5 and the chamber 61 so that the latter is subjected to a vacuum condition approximating that of the chamber 5. An air vent 70 is provided similar to the air vent 28 and serves to conduct air to a point adjacent the outlet 62 so that when the valve 63 is opened the air bubbles through the stored fuel supply and breaks the vacuum sufficiently to form a gradual feeding of the fuel to the nozzle in accordance with the demands of the motor.

By reference to Fig. 2, the operation of the carbureter will be understood to be as follows:—In this figure, the carbureter is shown with the supplemental chamber 3 serving as the supply for the main jet nozzle 11, since the chamber 2 has been in use, its fuel diminished to the low level necessary to cause the float 21 to lower sufficiently to close the valve 18 and it is being automatically replenished by a supply of fuel from the

conduit 12. In connection with the action of the chamber 3, it should be noted that while the valve 31 is open, it is not possible for the stored liquid fuel to rush or fall out suddenly, since the outlet 30 has its mouth submerged and as there is a vacuum or a partial vacuum in the chamber 3 owing to the port 37, this liquid fuel is consequently trapped in the chamber 3 and may only be discharged in small increments due to air bubbling through the opening 30 from the passage 42. As this action is a continuous one, the liquid fuel is gradually discharged through the opening 30 in sufficient quantities to replace the liquid fuel drawn out of the nozzle 11 by the operation of the motor. While this auxiliary feed to the nozzle 11 is in operation, the chamber 2 has been filling and the suction tending to hold the valve 18 closed is sufficiently strong to overcome for a limited time the tendency of the float 21 to force the said valve from its seat and the result therefore is that the float is submerged for this short period below the normal level of the liquid and when it does open the valve 18, it jumps quickly to its normal floating position and thereby snaps the valve 18 to its full open position. This action is promptly transmitted through the double levers to the valve 31 and causes this latter to close so that the auxiliary chamber 3 may be refilled or replenished and placed in condition to serve as a substitute for the active chamber 2 when the latter has been practically exhausted. In case both the chambers 2 and 3 should be relieved of a vacuum condition as would take place when the motor is at rest, then the overflow chambers 27 and 40 take care of the excess fluid fuel which could run by gravity out of the chamber having its valve open, though, of course, this excess fluid would be drawn back into its reservoir as soon as the vacuum conditions were restored. The respective vents 28 and 41 allow the air in these overflow chambers to escape so that the liquid may enter as will be understood. In connection with the replenishing of the chambers 2 and 3, it will be evident that when either is empty or nearly empty and the outlet valve for that chamber closed, there will be a building up of the vacuum to such an extent as to draw fuel from the low level supply tank by way of the conduit 13 and the inlet valve forced open so that the chamber is replenished in the required manner.

Referring to the auxiliary supply jets located adjacent the throttle, it will be evident, since the passage 51, from what I have called the slow speed jet, communicates with the motor intake directly there is a definite mixture supply available even when the throttle is closed and which is particularly adapted to give a rich mixture for

slow speed and starting purposes. This priming mixture is always available under starting conditions owing to the fact that the liquid level in the reservoir 10 rises considerably above the normal when the motor is at rest, because of the excess discharge from the vacuum relieved feeding chamber with the result that the liquid fuel overflows the nozzle 47 and rises well within the chamber 45. The other auxiliary jet which I have preferred to form as a movable part of the throttle is used more particularly for those conditions existing under intermediate speeds and where the throttle is partially open. In this construction, the discharge passage 59 for the auxiliary mixture has its outlet on the carburetor side of the throttle valve but moves with the throttle in such a manner that its outlet travels away from the wall of the intake passage and consequently approaches the central portion of the intake passage so that the fuel mixture discharged from it mingles directly with the main jet mixture without losses due to the liquid particles adhering to the walls of the passage.

The operation of the modified form of the device shown in Fig. 5 is substantially similar to that described for the preferred form, though it differs somewhat in minor details. Thus, for example, the chamber 2 is relatively large as compared to the chamber 61 and operates as the active supply chamber for the jet nozzle 11 while the chamber 61 is proportioned with a view to having it serve as an active chamber only when the chamber 2 is idle and is being replenished. Both chambers in this modification are provided with a liquid seal for the discharge outlet and the discharge of the fuel is directly controlled by the air which is allowed to bubble through the body of liquid and thus replace the minute quantity of fuel constantly drawn off from or required by the jet nozzle. The fuel supply for the chamber 61 is controlled by a float operated valve which opens only upon a lowering of the float and at which time the vacuum in said chamber is capable of drawing in a fresh supply of liquid fuel.

It will now be apparent that I have devised a complete unitary carburetor wherein the main reservoir or feeding chamber for the nozzle is continuously replenished from one or the other of the supply chambers 2 and 3 and these supply chambers are normally maintained under a vacuum condition and so controlled according to level conditions existing within them that one is supplying the main reservoir with fuel while the other is automatically being filled from a low level liquid supply. It will furthermore be noted that each of the fuel supply chambers is provided with a liquid sealed outlet, that is, an outlet the mouth of which

is normally below the operating level of the main reservoir and adjacent each outlet there is an air inlet which delivers air to the supply chamber which has its control valve open to the main reservoir.

It will furthermore be noted that the active supply chamber, by which is meant the one normally used by the main reservoir, has a volume of liquid fuel less than the liquid fuel volume of the other supply chamber whereby a considerable excess of liquid fuel is maintained in the reserve or inactive chamber for use or at least available while the active chamber is automatically being replenished by fuel drawn from the low level supply. In this connection it should be observed that the reservoir volume of the active supply chamber and also the reserve chamber may be varied, either by changing the dimensions of the chamber, or by providing chambers of the same dimensions, and employing floats of different dimensions. In either way the fuel volume of the chambers may be varied according to requirements.

While I have in the present drawings illustrated the carburetor as substantially rectangular and with the supply chambers arranged in opposed relation, it will be understood that I do not wish to be restricted in any manner to the location of the supply chambers with respect to each other or with respect to the main reservoir nor do I wish to be limited to any particular form or shape of the device since, obviously, it may be varied in these particulars in many ways without departing from the invention.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. In a device of the character stated, a carburetor having a main reservoir and separate liquid fuel chambers communicating with a low level liquid fuel supply, means to normally maintain both chambers under vacuum conditions, and means including liquid sealed outlets to control the admission of air to either chamber whereby said main reservoir supply is automatically replenished.

2. In a device of the character stated, a carburetor having a main reservoir and separate liquid fuel chambers communicating with a low level liquid fuel supply and having outlets respectively to said main

- reservoir, means to maintain both chambers under vacuum conditions, a plurality of air inlets communicating with said main reservoir below said outlets, and means controlled by the liquid level in either chamber for controlling the admission of air from one or the other of said air inlets to one or the other of said fuel chambers.
3. In a device of the character stated, a main reservoir and separate liquid fuel chambers communicating with a low level liquid fuel supply and having outlets respectively to said main reservoir, means to maintain both chambers under vacuum conditions, air inlets communicating with said main reservoir at substantially the normal liquid level and respectively adjacent said outlets, and float controlled valves for the respective chambers to alternately close and open said outlets whereby air is alternately admitted to said chambers to supply liquid fuel to said main reservoir.
4. In a device of the character stated, a carbureter having a main reservoir and separate liquid fuel chambers communicating with a low level liquid fuel supply, each chamber having a liquid outlet to said main reservoir, said outlets being normally sealed by the liquid in said main reservoir, and means under the control of level conditions to respectively admit air through said outlets alternately to said chambers, whereby a continuous supply of liquid fuel is delivered to said main reservoir.
5. In a device of the character stated, a carbureter having a main reservoir and separate liquid fuel chambers communicating with a low level liquid fuel supply, each chamber having a liquid outlet to said main reservoir, said outlets being normally sealed by the liquid in said main reservoir, means under the control of level conditions to respectively admit air through said outlets alternately to said chambers, and means to automatically replenish the supply of liquid fuel to one chamber while the other chamber is feeding the main reservoir.
6. In a device of the character stated, a carbureter having a main reservoir and separate liquid fuel chambers communicating with a low level liquid fuel supply, each chamber having a liquid outlet to said main reservoir, said outlets being normally sealed by the liquid in said main reservoir, means to normally maintain a vacuum condition in both chambers, means under the control of level conditions in said chambers to respectively admit air through said outlets respectively, a nozzle in communication with said main reservoir, and means to temporarily retain an excess of liquid fuel in case said vacuum condition is broken in said chambers whereby the main reservoir level is maintained at or below the nozzle discharge.
7. In a device of the character stated, a carbureter having a main reservoir and separate liquid fuel chambers communicating with a low level liquid fuel supply, means to normally maintain both chambers under vacuum conditions, an outlet from each chamber normally sealed by the liquid fuel in said main reservoir, a float in each chamber, valves controlled by the respective floats and operating to open and close the respective outlets, and air inlets to said main reservoir terminating adjacent the respective outlets whereby the opening of either valve admits air to one or the other chamber to cause liquid fuel to replenish said main reservoir.
8. In a device of the character stated, a casing forming a carbureting chamber, a main reservoir and two separate auxiliary supply chambers, each chamber communicating with a source of low level liquid fuel supply and adapted to deliver liquid fuel to said main reservoir, one of said chambers being actively operative and the other being in reserve, means rendering said active chamber of less fuel volume than said reserve chamber, means to normally produce a vacuum in both chambers and a nozzle for delivering liquid fuel to said carbureting chamber.
9. In a device of the character stated, a casing forming a carbureting chamber, a main reservoir and two separate auxiliary supply chambers, each chamber communicating with a source of low level liquid fuel supply and adapted to deliver liquid fuel to said main reservoir, valve controlled outlets from the respective chambers to said main reservoir, floats for respectively controlling the valves of said outlets, one of said floats being larger than the other so that the fuel volume of one chamber is less than that of the other chamber, means to normally produce a vacuum in both chambers, and a nozzle for delivering liquid fuel to said carbureting chamber.

In testimony whereof I have hereunto signed my name.

ALFRED WEILAND.
